UNITED STATES PATENT OFFICE.

LUTHER L. KNOX, OF AVALON, PENNSYLVANIA, ASSIGNOR TO KNOX PRESSED & WELDED STEEL COMPANY, OF PITTSBURGH, PENNSYLVANIA, A CORPORATION OF PENNSYLVANIA.

FURNACE-DOOR FRAME.

1,168,649.

Specification of Letters Patent.

Patented Jan. 18, 1916.

Application filed April 17, 1915. Serial No. 22,080.

To all whom it may concern:

Be it known that I, LUTHER L. KNOX, a citizen of the United States, residing at Avalon, in the county of Allegheny and State of Pennsylvania, have invented a new and useful Improvement in Furnace-Door Frames, of which the following is a full, clear, and exact description, reference being had to the accompanying drawings, forming part of this specification, in which—

Figure 1 is a front elevation of a portion of a furnace equipped with my improved door frames. Fig. 2 is a section on the line II—II of Fig. 1. Fig. 3 is a view partly in plan and partly in section of the furnace structure shown in Fig. 1. Fig. 4 is a top plan view, partly broken away, of one of the door frames. Fig. 5 is a front elevation, partly broken away, of one of said frames, and Fig. 6 is a section on the line VI—VI of Fig. 5, and also partly broken away.

My invention has relation to furnace door frames and more particularly to water cooled frames.

The object of the invention is to provide a water cooled door frame having a member which forms one of the skew backs for the roof arch of the furnace and which also constitutes the top or wall of the door opening of the furnace. Also to provide a door frame of this character which consists in other novel features hereinafter more fully pointed out.

In the accompanying drawings the numeral 2 designates the frame of a furnace, which may be in general of any usual or suitable character, and which supports the masonry work 3.

4 designates the roof arch of the furnace, which is supported at its rear edge on the masonry wall 3^a and at its front edge by the skew back 5 formed by the downwardly and inwardly sloping surface of a hollow water cooled door frame member which extends transversely above the door opening 6.

7 designates the furnace doors.

The member 5 is supported on the masonry work at each end and may also be suspended from the frame work 2 in the manner indicated at 8, or in any other suitable manner. Its central portion 5^a is offset outwardly with reference to its end portions, forming the recesses 5^b through which extend the hollow water cooled legs 9 of the frame. These legs are preferably of L-

shape in cross section, having the inclined surfaces 9^a upon which the door 7 seats and slides, these surfaces at their upper ends being in the plane of the outer surface of the central part 5^a of the member 5. The leg members 9 may be secured to the member 5 in any suitable manner, as by means of the bolted lugs 10.

Any suitable system of connections may be employed for maintaining the circulation of water through the frames. In the arrangement shown, a water supply pipe 11 extends across the front of the furnace above the furnace doors with a connection 12 (see Fig. 3) leading downwardly within each of the leg members 9. At its upper end each of said members has a pipe connection 13 leading upwardly to the upper front portion 4^a of the furnace, where it is shown as discharging into a funnel 14 mounted on 70 and connected to a pipe 15. This pipe has connections 16 which telescopically engage the doors 7 to supply water thereto.

13^a designate outlet connections from the end portions of the member 5, and also discharging into the funnels.

17 designate outlet connections for the doors which may have portions 18 which telescopically engage the furnace frame between the doors and discharge therein, the water being carried off of this frame in any suitable manner.

The pipes 11 and 15 may have the connection 19 provided with a valve 20 so that in case of emergency water can be supplied directly from the pipe 11 to the pipe 15 and thence into the doors through the connections 16. The water supply system shown is illustrative only and any suitable system may be employed.

The advantages of my invention result mainly from the provision of the water cooled door frame member 5, which not only forms the skew back for supporting the roof arch at the front of the furnace, but also the upper wall of the door opening of the furnace. By the provision of this member, I avoid the necessity for any masonry or brick work arch over the door opening and also provide a direct cooling means for supporting a roof arch. The members 5 and 9 being independent of each other any one of the members can be renewed when necessary without disturbing the remainder of the frame.

105

110

I claim:

1. A furnace door frame, comprising a hollow water cooled member extending transversely over the door opening of the furnace, said member having an inner beveled side wall forming a skew back directly supporting the roof arch of the furnace, and having its bottom wall constituting the top of the furnace door opening; substantially as described.
2. A furnace door frame; comprising a hollow water cooled member extending transversely over the door opening of the furnace, said member having an inner beveled side wall forming a skew back directly supporting the roof arch of the furnace, and having its bottom wall constituting the top of the furnace door opening, the outer surface of said member forming a door seating and guiding surface; substantially as described.
3. A furnace door frame, comprising a hollow water cooled member extending transversely over the door opening of the furnace, said member having inwardly offset end portions, and separate water cooled leg members removably seating in said offsets; substantially as described.
4. A furnace door frame, comprising a hollow water cooled member extending transversely over the door opening of the furnace, said member having inwardly offset end portions, and separate water cooled leg members seating in said offsets, said leg members having outer guiding surfaces, and the central portion of the transverse member extending forwardly into the plane of said guiding surfaces; substantially as described.
5. A furnace door frame, comprising a transverse member extending over the furnace door opening with its inner surface forming a skew back for the roof arch of the furnace, and its lower surface forming the top at the furnace door opening, together with leg members extending at either side of the outer opening, the central portion of said transverse member being extended forwardly between said leg members; substantially as described.

In testimony whereof, I have hereunto set my hand.

LUTHER L. KNOX.
